UNITED STATES PATENT OFFICE.

MICHAEL J. O'CONNOR, OF BLOOMINGDALE, NEW JERSEY.

MUFFLER FOR EXPLOSIVE ENGINES.

1,412,416.

Specification of Letters Patent. Patented Apr. 11, 1922.

Application filed August 21, 1919. Serial No. 319,002.

To all whom it may concern:

Be it known that I, MICHAEL J. O'CONNOR, a citizen of the United States, residing at Bloomingdale, in the county of Passaic and State of New Jersey, have invented certain new and useful Improvements in Mufflers for Explosive Engines, of which the following is a specification.

This invention relates to mufflers for exhaust lines and has for an object to provide a muffler embodying new and improved features for insuring continuous discharge from the final discharge orifice. A further object of the invention is to provide a muffler which shall break up the exhaust from the ordinary exhaust line into a plurality of separate individual exhausts which are exhausted at different periods, whereby the several individual exhausts from the engine 20 are converted into a practically continuous exhaust at the exhaust orifice.

A further object of the invention is to provide a muffler which will break up the separate impulses of the normal exhaust into substantially a noiseless continuous discharge while offering the minimum resistance and consequently the minimum back pressure.

Referring to the accompanying drawings 30 which form a part hereof and on which similar reference characters indicate similar parts,

Figure 1 is a longitudinal, vertical sectional view through the major diameter of the device, and

Figure 2 is an end elevation of the conical passage as indicated by line 2-2 of Figure 1.

The improved invention which forms the 40 subject matter of this application is adapted to be attached to an ordinary exhaust line 10 of an internal combustion engine. The device may be attached to the exhaust line in any approved manner. As shown at Figure 1 a collar 11 is employed screw-threadedly connected with the extremity of the exhaust line 10. It is to be understood, however, that the manner of attaching the collar 11 is immaterial to the present invention.

50 Collar 11 provides a shoulder 12 upon which is seated the exterior cone 13. The exterior cone 13 is at its base cut upon a plane inclined to its axis, and is provided internally with a plurality of ribs. Some 55 of the ribs, as 14, extend throughout the length of the cone and meet at a common

point or apex at 15 substantially axially of the exhaust line 10.

Intermediate the long ribs 14 shorter ribs 16 are introduced so that with the device 60 provided with five long ribs, as shown at Figure 2, and five short ribs, also shown at Figure 2, all exhaust from the exhaust line 10 will be driven into ten separate portions when it is exhausted at the base of 65 the cone. While the drawing shows the number of long and short ribs combined as 10 it is to be understood that the number of such ribs is in no way limited to or by a specific disclosure and the invention comprehends the use of any number of ribs 70 convenient or desirable.

At some point in the length of the long ribs 14 an air duct 17 is introduced in such manner that air is taken in from the exterior, as indicated more particularly at Figure 1, and discharged part upon each side of the rib with which it is associated. In this manner air is mixed with the exhaust gases to cool the gases before they are further discharged. To limit the gases an internal cone 18 is employed which fits the inner edges or margins of the ribs 14 and 16. This limiting cone 18 forms a plurality of 80 tapered passages between the cones 13 and 18 extending from the point of the coupling 11 to the base of the cone. It will be noted that by reason of the inclination of the base of the cone relative to an axis that the 85 length of travel through the passages shown in Figure 1 as at the bottom of the figure is considerably less than the length of travel through the passages shown at the top of the figure and that the passages intermediate the points shown at the top and bottom respectively vary in such length from maximum to minimum. The exhaust from the line 10 will therefore be broken up and delivered at the base of the cone at different 90 intervals. At the base of the cone a return 95 guide 19 is provided in the form of a casting having divisions 20 corresponding with and abutting the several ribs 14 and 16, so that when the exhaust thus divided as hereinbefore described, engages the return curve 100 105 it also engages between the partitions 20 and is directed as indicated by the several arrows to the interior of the inner cone 18. The return curve member 19 also serves as a means for holding the device in assembled 110 condition, bolts 20 being inserted through ears in the curve member 19 and into screw-

ears in the curve member 19 and into screw-

threaded sockets in the sleeve 11. By tightening the bolts 21 the curve member 19 is clamped rigidly against the outer cone 13 and by reason of the partitions 20 against 5 the base of the inner cone 18 whereby the entire device is connected and held in unitary condition.

The curve member 19 is provided with an opening 22 through which the gases ejected 10 into the interior and to the apex of the inner cone 18 are exhausted. About this opening 22 a housing 23 is provided with a closure at the extremity indicated at 24 which is secured to the device to form an organized 15 structure by the bolts 25 inserted into the curve member 19. The chamber formed by the housing 23 and closure 24 is provided with an exhaust orifice produced by the branch 26 preferably, though not necessarily, cast integral with the closure 24. A second branch 27 is also associated with the branch 26 with a damper or valve 28 hinged at 29 so that the said damper 28 may be swung by any approved and manual means 20 to open communication through branch 26 or 27. The branch 27 is also preferably screw-threaded as at 30 so that any approved or desired signal device may be attached thereto and by manipulating the device 25 30 may be actuated as found necessary or desirable.

In operation it will be obvious that the exhaust gases from the exhaust line 10 will engage the several ribs 14 at their apex 15 and be divided into as many portions as there are ribs 14 before entering between the outer cone 14 and the inner cone 18. The gases thus divided will also receive air through the air ports 17 and encountering 35 the ends of the short ribs 16 will again be divided. The passages formed by the ribs 14 and 16 are tapered and therefore continually enlarge in carrying capacity as they approach the base of the cone. The portion of 40 divided gases given the minimum passage to traverse, that indicated at the bottom of Figure 1, will engage the curve member 19 and be ejected into the interior and apex of the inner cone 18 first. The gases through 45 the passage next longer will follow and be rapidly followed in succession by the gases from the various lengths of passages until the gas through the passage of maximum length, that shown at the top of Figure 1, 50 has been discharged. As all of the gases discharged from all of the passages of various lengths will be ejected to the apex of the inner cone 18, all start on their movement to the outlet orifice 26 from the same point so 55 that the varying lengths of passage is not lost in the passage from the inner cone to the outlet orifice, but the relation of the stepped discharge is maintained. By attaching a signal to the screw-threads 30 and 60 properly manipulating the valve 38 a con-

tinuous alarm is provided not characterized by the pulsation of sound as is usually the case with signals attached to the exhaust line. It is obvious of course that while the signal to be attached to the threads 30 70 would be a horn of ordinary type, any mechanical means for operating the signals or other device may be attached in any manner found desirable.

Having thus fully described my said invention, what I claim as new and desire to secure by Letters Patent, is:

1. A muffler comprising a chamber, conduits discharging into the chamber at varying distances from one end, means for reversing the direction of the exhaust gases between said conduits and said chamber and means for conducting the exhaust gases away from the chamber, substantially as set forth. 80

2. A muffler comprising a chamber, conduits discharging into the chamber at varying distances from one end, means for reversing the direction of the exhaust gases between said conduits and said chamber, means to attach to an exhaust-line terminus 90 at the said end and means to divide each exhaust impulse to discharge through all of said conduits substantially as set forth. 95

3. A muffler for explosive engine exhausts, comprising a conical member adapted to be 100 attached to an exhaust line, a second conical member spaced from the first conical member, the said associated conical members being cut upon a plane inclined to the axis, partitions interposed between the conical members, producing by reason of different lengths, means to discharge the gases from the several passages to a common point, and means to receive and educt the gases from such common point. 105

4. A muffler for explosive engines, comprising a conical member open at its apex, a second conical member disposed within the first conical member and closed at its apex, ribs formed between the conical members dividing the intervening space into a plurality of passages increasing in carrying capacity from the apex to the cone, means disposed at the base of the cone for directing the discharged gases into the interior and apex of 115 the inner cone, and means to receive and educt the gases from the inner cone. 116

5. A muffler for explosive engines, comprising a conical member having an opening at its apex, a conical member disposed with- 120 in the first conical member and closed at its apex, both of said conical members having their bases cut upon a plane inclined to the axis of the cone, ribs interposed between the conical members dividing the intervening space into a plurality of passages increasing in carrying capacity and varying in length, means at the base of the cone to receive the discharge gases and direct them to the interior and apex of the inner cone, 125 130

and means to receive and educt the gases from the inner cone.

6. A muffler for explosive engines comprising a cone having an opening in its apex, 5 means for connecting the opening in the cone with the exhaust line from the explosive engine, a second cone disposed within and spaced from the first mentioned cone, ribs interposed between the cones forming a plurality of passages from the apex to the base 10 of the spaced cones, said cones being cut upon a plane at their bases inclined to the axis producing thereby variation of length of the said several passages, a curve member 15 secured to the base of the combined cones and providing a passage directed to the interior and apex of the inner cone, and a housing positioned at the opening of the curve member adapted to receive and educt 20 gases from the inner cone.

7. A muffler for explosive engines, comprising spaced members providing a plurality of passages communicating with the exhaust line of the engine, which said passages vary in length, means to receive the 25 gases from the passages of varying lengths and discharge them to a common point, a housing positioned to receive the gases deflected from the common point, an egress orifice formed in the housing, a second orifice 30 communicating with the first mentioned ribs and providing means for attaching a signal device and a manual valve interposed in the egress orifice adapted to direct the gases through either discharge opening. 35

In witness whereof, I have hereunto set my hand and seal at Washington, D. C., this 20th day of August, A. D. nineteen hundred and nineteen.

MICHAEL J. O'CONNOR. [L.s.]
